UNITED STATES PATENT OFFICE.

JEROME HAVERLY, OF OAKLAND, CALIFORNIA.

MERCURY SEPARATOR.

Original application filed April 2, 1919, Serial No. 286,954. Divided and this application filed July 23, 1920. Serial No. 399,538.

To all whom it may concern:

Be it known that I, JEROME HAVERLY, a citizen of the United States, residing at Oakland, in the county of Alameda and State of California, have invented certain new and useful Improvements in Mercury Separators (the same being a division of my copending application filed Apr. 2, 1919, Serial No. 286,954), of which the following 10 is a specification, reference being had to the accompanying drawings.

This invention relates to certain improvements in mercury separators, and it is an object of the invention to provide a novel and improved device of this general character especially designed and adapted for use in connection with tailings or placer material.

It is also an object of the invention to 20 provide a novel and improved device of this general character including an amalgam box having coating therewith means for forcing the auriferous or other value bearing material below the mercury surface to 25 assure the desired separation of the values.

The invention consists in the details of construction and in the combination and arrangement of the several parts of my improved mercury separator whereby certain 30 important advantages are attained and the device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein:

Figure 1 is a view in front elevation illustrating an amalgam box constructed in accordance with an embodiment of my invention.

45 Figure 2 is a vertical sectional view taken substantially on the line 2—2 of Figure 1, and

Figure 3 is a fragmentary view in top plan of the amalgam box as herein disclosed 50 with the feed members omitted.

As disclosed in the accompanying drawings, A denotes a substantially horizontal amalgam box of desired depth and having a rearward and upward inclined extension 55 1. The extension 1 is of a depth less than

the depth of the box A proper and has its upper or rear portion free and unobstructed and defined by a depending flange 2.

Secured to the forward portions of the end walls 3 of the box A are the upwardly directed standards 4 provided at their upper ends with the boxings 5 which rotatably support the opposite end portions of a shaft 6 extending longitudinally of the box A. The front longitudinal wall 7 of the box A is provided with a plurality of spaced and inwardly directed blocks 8 to each of which is held by a clamp 9 a vertically disposed feed cylinder or pipe 10. Each of the cylinders or pipes 10 is open at its opposite ends and the lower end portion of said cylinder or pipe extends below the mercury level a of the box A but is spaced from the bottom 11 of the box. The opposite or upper end portion of the cylinder or pipe 10 terminates a distance above the box A but below the shaft 6.

The opposite end portions of each of the cylinders or pipes 10 have disposed radially thereacross the members or bearings 12 which rotatably support the opposite end portions of the vertically disposed shaft 14 of a spiral S. The spiral S snugly fits within the feed chamber between the members or bearings 12 and its direction of rotation is such as to force downwardly the auriferous or other value bearing material delivered within the upper end of the cylinder or pipe 10 so that such material will be positively forced below the mercury level a to assure the separation of the values from the material.

The upper end portion of each of the shafts 14 is operatively connected through the medium of the bevel gears 15 with a shaft 6 so that upon requisite rotation of the shaft 6, all of the spirals S will be caused to operate in unison. The shaft 6 may be driven in any desired manner but preferably in accordance with the construction and arrangement of parts disclosed in my copending application, Serial No. 286,954, filed April 2, 1919, and of which the present application is a division.

As illustrated in the accompanying drawings, the shaft 6 is in driven connection through the medium of the chain 17 with a shaft 19, said shaft 19 being disposed longitudinally of the box A exteriorly thereof and supported for rotation by the outstand-

ing bearings 20 secured to the front wall 7. The shaft 19 is adapted to be coupled in any desired manner with a suitable source of power and which connection is generally indicated by the sprocket 21.

Arranged rearwardly of the feed pipes 10 and above the box A is a spray pipe 59 for the purpose of thinning the waste or tailings as the same rise to the top of the mercury within the box A to facilitate the feeding of the same to the shaking pan (not shown).

I also find it of advantage to provide the forward portion of the box A with a collecting well 62 provided with a normally closed opening 63 so that the collected values may be readily withdrawn therefrom.

From the foregoing description it is thought to be obvious that a mercury separator constructed in accordance with my invention is particularly well adapted for use by reason of the convenience and facility with which it may be assembled and operated, and it will also be obvious that my invention is susceptible of some change and modification without departing from the principles and

spirit thereof and for this reason I do not wish to be understood as limiting myself to the precise arrangement and formation of the several parts herein shown in carrying out my invention in practice except as hereinafter claimed.

I claim:

A separator of the character described comprising an elongated amalgam box having a side wall and end walls, a plurality of spaced cylinders disposed in engagement with the inner face of the side wall of the box, the opposite side portion of said box being open, said box having a stepped and inwardly inclined bottom, the longitudinal portion of the bottom only immediately beneath the lower ends of the cylinders being formed into a trough, said stepped bottom extending from the inner edge of the trough to the open side portion of the box, the trough having an outlet, and means movable in said cylinders for forcing matter into the trough of said bottom.

In testimony whereof I hereunto affix my signature.

JEROME HAVERLY.
